STEAM IRONS

Justice H. Beach, Canton, Ohio, assignor to The Hoover Company, North Canton, Ohio, a corporation of Ohio

Application September 2, 1954, Serial No. 453,851

2 Claims. (Cl. 38—77)

The present invention relates to electric steam irons and more particularly to providing a pressure head to the water discharged into the steam generator.

An object of the invention is to provide a steam iron having a chamber defining a water head to obtain uniform flow of water to the steam generator as the water level in the reservoir decreases. Another object is to provide a water head in a steam iron and which produces greater pressure than the water in the reservoir as the water level is reduced. A further object is to provide a steam iron having a water head chamber for the water discharged into a steam generator and which is refilled when the iron is moved away from and to the ironing position. Other objects and advantages of the invention will become apparent from the following description and drawings wherein:

Figure 1 shows the iron partly in section and in ironing position with the water head chamber refilled with water, and

Figure 2 illustrates the iron in upended rest position and the water collected at one end of the reservoir.

The embodiment of the invention herein disclosed comprises a sole plate 10, a water reservoir 11, cover shell 12 and a handle 13. Arranged in the sole plate 10 is an embedded U-shaped heating element 14 to heat the ironing surface 15 and a steam generating chamber 16 which communicates with a steam passageway 17 provided with unshown ports for discharge of steam on the material to be ironed. A cover plate 18 is attached by screws 19 to the sole plate 10 and forms part of the steam passageway 17 and is provided with an opening 20 above the steam generator 16. A member 21 is secured to the cover plate 18 and is provided with an apertured concave seat 22 in which a boss 23 projecting from the reservoir 11 rests and has its end 24 extending into the steam generating chamber 16. The boss 23 is threaded at 25 to a sleeve 26 secured to the bottom wall 9 of the reservoir and has a discharge port 27 leading from the reservoir to the steam generating chamber 16 for passage of water thereto. The reservoir 11 is positioned above the sole plate 10 by resting on a bracket 28 and the boss 23 bearing against the concave seat 22.

A thermostat 30 is suitably secured to the sole plate 10 and has a stem 31 extending through a tube 32 in the reservoir 11 and an opening 33 in the cover shell 12 for attachment to a dial 34 which is rotated to operate the thermostat for obtaining the desired temperatures in the sole plate 10. The cover shell 12 is removably secured to the sole plate 10 by a bolt 35 passing through a tube 36 in the reservoir and threaded into a nut 37 rigid on the sole plate 10.

The handle 13 has its rear leg 38 attached to the cover shell 12 by a screw 39, and its front leg 40 is secured by a bracket 41 and screw 42. A projection 43 is provided at the rear end of the handle 13 and cooperates with end 44 of the shell 12 to support the iron in upended rest position as shown in Figure 2.

A fill tube 45 is staked at 46 to the top wall 47 of the

2

reservoir 11 and projects through the cover shell 12 into a recess 48 in the handle front leg 40 and is provided with a fill opening 49 and port 50 for entrance of water into the reservoir 11. A valve stem 51 is slidably supported in the fill tube 45 by a bracket 52 and is provided at its lower end with a needle valve 53 to control flow of water through the port 27 into the steam generating chamber 16. The upper end of the valve stem 51 is provided with an elongated opening 54 receiving a pin 55 mounted on a valve actuator 56 pivotally supported at 57 in the handle leg 40, and an over center acting spring 58 maintains the needle valve 53 in open or closed position to control the water discharge port 27.

The reservoir 11 includes the bottom and top walls 9—47 and a partition or baffle 60 all secured together by a rolled bead 61, and the tubes 32—36 have a water tight connection 62 with the walls and partition of the reservoir. The partition 60 divides the reservoir 11 into lower and upper water chambers 63 and 64 respectively, and is inclined downwardly from the rear end 65 to cause water on the partition 60 to flow toward the front end 66 of the reservoir. A pair of ports 67 and 68 are formed in the partition 60, and tubular walls 69 extend upwardly therefrom into the upper water chamber 64 to trap water therein as shown in Figure 1. Secured in water tight relation to the underside of the baffle 69 and the reservoir lower wall 9 is a tubular member 70 the upper end of which is exposed to an opening 71 in the baffle 69 for entrance of water from the upper chamber 64. The tube 70 encloses the opening 72 to the discharge port 27 and is of sufficient height to form a chamber 73 for water which will provide a head or pressure to the water being fed to the discharge port 27.

When using the iron for steam ironing the reservoir 11 is first filled with water by placing the iron in its upended rest position as shown in Figure 2 and water is poured into the fill opening 49 and passes through the port 50 into the upper water chamber 64 and initially collects at the lower end 65 thereof until the volume of water rises to the port 67 and then it passes therethrough to thereafter fill the chambers 63 and 64 with water. The dial 34 is then moved to its steam position to heat the sole plate 10 and the steam generator 16 and after sufficient time has elapsed for such heating the actuator 56 is moved rearwardly to shift the valve stem 51 and uncover the discharge port 27 to the generator 16, thereafter the iron is placed in its ironing position with the sole plate 10 resting on the material to be ironed.

At the beginning of the ironing period the water fills the two chambers 63—64 and the height of the water is above the water head chamber 73 to thereby provide sufficient water pressure to the port 27 to uniformly feed water to the generator 16, and thus furnish a constant steam supply. When the water level is reduced to below the partition 60 the head for the discharge port 27 initially provided by the water in the upper chamber 64 disappears. In order to reestablish the water pressure the iron is upended to its rest position shown in Figure 2 causing the water in the lower chamber 63 to flow through the port 67 into the upper chamber 64. Upon returning the iron to its ironing position as shown in Figure 1 the water collected in the upper chamber 64, while the iron was in rest position, is distributed along the partition 60 and through the opening 71 into the chamber 73 to provide a water head therein of greater height than could be supplied by the water level 74 in the reservoir 11. The tubular extension 69 of the ports 67—68 project above the partition 60 to trap additional water 75 which flows through the opening 71 into the chamber 73 to replenish the latter with water without the necessity of moving the iron to its rest position and returning it to its ironing position.

From the foregoing it will be perceived I have provided a steam iron wherein as the water level in the reservoir is lowered a head of water greater than that supplied by the lowered water level is obtained by shifting the iron to its rest position and back to its ironing position, to thereby insure a more uniform supply of water to the steam generator and consequently a constant supply of steam to the fabric being ironed.

While I have shown and described but one embodiment of my invention, it is to be understood that this embodiment is to be taken as illustrative only and not in a limiting sense. I do not wish to be limited to the particular structure shown and described but to include all equivalent variations except as limited by the scope of the claims.

I claim:

1. In a steam iron, a water reservoir, a steam generating chamber, a discharge port in said reservoir for passage of water to said chamber, means supporting the iron in rest position, means in said reservoir defining a water head chamber of restricted volume compared to said reservoir and connected to said discharge port to provide a greater head to the water passing through said discharge port when the iron is in its ironing position than the head of water in said reservoir, partition means separating said reservoir into upper and lower water chambers, means defining a port in said partition for passage from said lower chamber to said upper chamber of water displaced in said lower chamber by the action of gravity upon moving the iron to its said rest position to thereby replenish the upper chamber with water, means trapping added water in said upper chamber.

ber upon moving the iron to its ironing position, and means defining an opening in said partition for passage of trapped water from said upper chamber to said water head chamber when the iron is in its ironing position to reestablish a water head at said discharge port.

2. In a steam iron, a water reservoir, steam generating means, a discharge port in said reservoir for passage of water to said steam generating means, means defining a water head chamber of restricted volume compared to said reservoir, said water head chamber projecting from said discharge port inwardly of said reservoir and having its upper inlet end above the water level in said reservoir when the iron is in ironing position to provide a greater head to the water passing through said port than the head of water in said reservoir, baffle means in said reservoir and including means for entrance thereto of water displaced in said reservoir by action of gravity when said iron is moved to non-ironing position, means to retain displaced water in said baffle means when said iron is returned to ironing position, and means connecting said baffle means to said inlet of said head chamber for conveying retained water to said head chamber to refill the latter with water upon returning the iron to its ironing position.
